UNITED STATES PATENT OFFICE.

GEORGE A. HENDERSON, OF ST. ALBANS, WEST VIRGINIA.

AEROPLANE.

1,405,917.

Specification of Letters Patent. Patented Feb. 7, 1922.

Application filed April 17, 1918. Serial No. 229,146.

To all whom it may concern:

Be it known that I, GEORGE A. HENDERSON, a citizen of the United States, residing at St. Albans, in the county of Kanawha and State of West Virginia, have invented a certain new and useful Improvement in Aeroplanes, of which the following is a specification.

My invention has relation to the art as disclosed in my 1915 United States patent for improvement in aeroplanes, Number 1,164,717, of suspending an aeroplane in the air through its relationship to agitated air as distinguished from such suspension resulting from its traction or propulsion through still air; and my objects are:

To produce from free air such mechanically generated air currents as have heretofore been dissipated in aeroplanes' wakes; to establish their constant magnitude and to vary their absolute incidence or angle of attack during flight of the machine as a whole, for the purpose of increasing and controlling resistance to a plurality of assembled propellers and aerofoils therein acting reciprocally with each other to suspend, to vertically lift and lower and to move the machine in the air.

More particularly my objects are (a) to provide means for establishing definitely deflected air currents of predetermined volume and velocity, and to direct the force of their resistance to create constant centers of pressure on to practically disposed aerofoil area;

(b) As distinguished from, (an aerofoil,) using free air, an object is to establish and to maintain a system of forces of air resistance of a plurality of aerofoils assembled in horizontal and vertical tandem, in which system said forces are sufficiently parallel with each other and constant in magnitude to produce a plurality of metacentric curves reduced to points, or envelopes of the consecutive positions of the aforesaid controlled air resistance;

(c) To direct the latter curves to arbitrarily fixed positions of said resultant forces of air resistance on the propellers and aerofoils so positioned in their relation to each other to accomplish the prime object of my invention, and

(d) To provide increased suction along the top surfaces of all aerofoils to increase

their lifting capacity in degree greater than 55 that exerted as lifting force by air pressure on their under-sides.

The accompanying drawings show one embodiment of my invention. In describing them it is premised that its broader 60 features are capable of various embodiments within the scope of the appended claim.

In the drawings Fig. 1 is a side elevation in section of a machine illustrating my invention, Fig. 2 is a vertical cross section 65 thereof with certain parts omitted for clearness of illustration, Fig. 3 is a detail view of Fig. 1 showing the planes in inclined position with the general courses of the air resistance thereon indicated; and showing 70 a view in detail, of the means of adjusting the planes, and of their internal bracing with relation to the machine as a whole.

The letter F designates the frame work of the machine, S a central driving shaft 75 revolved by motors, M, in cars C, located below the central shaft S, which operates auxiliary shafts S' by vertical shaft drives S² (Fig. 3), carrying propellers P rigidly anchored to shafts S', the shafts being 80 braced within the frame work of the machine.

Planes A are anchored at practically determined distances in the rear of propellers P. The upper planes A may be of 85 greater dimensions than the lower planes, their aspect ratio being approximately 8, though I do not limit myself to the number of planes, their size, shape or to their aspect ratio as stated. They are preferably 90 internally reinforced in the manner illustrated in Fig. 3, in which A—A are cross sectional views of the planes or aerofoils. A¹ is a central shaft running longitudinally through the aerofoils and pivotally mounted in journals A² at either end of the plane within the frame work of the machine, F. A³ is a flexible sheet of steel rigidly anchored to shaft A¹ a substantial part of its length and internally bracing, in the form 100 shown, the aerofoils A. At a plurality of equally distant locations on shaft A¹ and rigidly anchored thereto I provide cams A⁵, A⁶, movably connected with paralleling shafts A⁶, S⁶ with uprights A⁷, A⁷, operable vertically by sliding connecting rods A⁸, A⁸ on common control shaft A⁹, moved horizontally of the machine by the oper-

ator's manipulation of lever A^{10} , intermeshed at the point A^{11} through connection A^{12} .

- The common shaft A^8 , when manually moved horizontally, acts through the rods A^8 , pivoted and braced within the framework F , of the machine, to lift or lower the up-rights A^7 according to the direction in which the lever A^{10} is moved, and the 10 inclination of the cams A^5 fixing in turn the inclination of the aerofoils thereto connected in the manner illustrated, fixes the angle of incidence of the air resistance which is horizontally directed to their undersides 15 by the operation of propellers P as herein described.

The propellers P , of usual construction, are variously bladed numerically, preferably from two to four, inclusive, and their respective revolutions per minute are predetermined by tests and fixed in their relation to each other consistent with the maximum resistance of air currents to be presented to their forward surfaces in the manner hereinafter described.

When on earth the machine rests on skids U attached to the underpart of the framework F . The planes or aerofoils A are adjustably inclined as shown in Fig. 3 and are then subjected to currents of air generated by the propellers P in direction $L-D$ which currents are deflected by the planes in direction oblique to perpendicular on the line $B-A-C$. For example I have illustrated 35 in Fig. 3 a plurality of currents of air generated by the forward propellers, and directed horizontally backwardly to the entering edge of the aerofoil at fixed angles of attack thereon when inclined, as shown, on a 40 line corresponding to zero lift when the current is in the direction indicated, thus providing absolute incidence, viz., centers of pressure at the point of intersection of the resultant force of air resistance to the line 45 $B-A-C$, representing that of zero lift in this instance.

The propellers creating, as they inevitably do, a plurality of paralleling air currents of constant magnitude, they are thus applied 50 to a plurality of points on the under curved surface of the aerofoils along the general direction of the zero line represented by the inclination of the planes in Fig. 3, (equivalent to the aerofoil area of the planes in 55 Fig. 1). These currents, turning around their points of application, but having their magnitude and velocities maintained by the constant operation of the propeller, remain approximately parallel to each other, with 60 the result that the resultant force turns at the definite point, viz., that fixed by the uniform inclination of all aerofoils in vertical and horizontal tandem in relation to the propellers intervening in the manner 65 illustrated in the drawings, with the result

that a series of alternatingly paralleling air currents of constant magnitude are created, directed backward, then obliquely on the line $B-A-C$, thence again backward on the line $L-D$, thence again obliquely on the 70 line $B-A-C$, thence, under the influence of the lower third propeller in vertical tandem, again backward on the line $L-D$, thence obliquely to down on the line $B-A-C$, to the atmosphere, where the currents, representing dissipated force, form in space a series of metacentric curves of general direction horizontal of and in the wake of the machine as a whole. 75

In combination with the tractive force applied to all of the propellers in the direction $L-D$, direction of the machine is, in the above illustrated instance, resolved by those forces in direction of a line drawn between the lines $B-A-C$, and $L-D$, and when the machine is released from provided anchorage on the earth, with said forces preliminarily so applied, no initial momentum of the machine as a whole with reference to the surface of the earth, is required 90 for its flight. Reliance on increased suction of air from the top of the machine forward, down and thence backwardly and oblique to down, in the course above described, is had for creating lifting power in force superior 95 to that exerted by the fixed currents on the underside of the planes.

The normal tendency of a current (so created and deflected), to assume direction parallel to the moving body as a whole (as distinguished from the tangent of its trailing edge) is relied on as an aid to the tandem propellers in the center and lower rows to deflect to horizontal, the oblique forces of air, to be again deflected obliquely by 100 the aerofoils in the manner described. 105

When in flight, the designed changing of the inclination of all aerofoils A from their inclined positions as shown in Fig. 3 toward those positions illustrated in Fig. 1, resolves 110 direction of the machine toward the line $L-D$ and the general direction of the air currents in the opposite direction, at increased velocities in relation to each other. Conversely, when in flight the designed 115 changing of the inclination of all aerofoils A from their inclined positions as shown in Fig. 3 toward the perpendicular line $A-O$ (but in no event to perpendicular), acts to equalize all forces present in the machine 120 viz., that resistance and suction to resolve direction on the line $B-A-C$, that traction to resolve direction on the line $R-L$, and gravity to resolve direction on the line $B-A-C$, so that with gravity initially 125 overcome, as hereinabove described, and with direction fixed by dominating forces manually controlled within the craft, the latter forces are practically manipulated to effect its immobility in mid-air. 130

In flight, direction is fixed and stability aided by manual operation of horizontal and vertically disposed rudders R and R' and vanes V and V' of practical construction known to the prior art, and set within the influence of said air resistance entirely encircling the machine as a whole, to the exclusion of all outside air interferences.

I claim:

- 10 An aeroplane comprising a plurality of sets of superposed aerofoils arranged in tandem, superposed motor driven propellers located in advance of the aerofoils acting

to create tractive forces and to provide a series of paralleling air currents in combination with means for changing the inclination of the aerofoils and the direction of the aeroplane.

In testimony whereof I have affixed my signature in the presence of two witnesses 15 20 this thirteenth day of April, 1918.

GEORGE A. HENDERSON.
